ADJUSTABLE SPACEBAND INDICATOR

Edward S. Larson, Chicago, Ill., assignor, by
means assignments, to Teletypesetter Corpora-
tion, a corporation of Delaware

Application January 14, 1933, Serial No. 651,731

25 Claims. (Cl. 164—112)

This invention pertains to type-setting systems and apparatus and especially to perforators and counters which may be utilized for preparing a perforated tape for the automatic control of composing machines of the line-casting type.

The principal object of the present invention is to provide a keyboard perforator and counter of universal range, utilizable in the preparation of control strips for the automatic control of line-casting and composing machines which contemplate the use of various fonts of type and different sizes of spacebands.

One of the specific objects of the invention is to provide, in a keyboard perforator and counter, means which is extremely flexible as well as adjustable, for adapting the keyboard apparatus for use in type-setting systems employing an indefinite number of sizes of expandible justifying matrices or spacebands.

As is commonly known in the typographical art, the slugs or lines of type produced by composing machines of the line-casting type are made through the instrumentalities of matrices which consist of small brass units carrying indented characters in their edges and which are of different thicknesses due to the fact that the characters vary in width. As is understood in the art the matrices of a particular set size and style are assembled into separate groups known as fonts. When these matrices are assembled into a line of predetermined definite length, the number of matrices necessary to complete the line varies with the particular matrices used. The length of the line, therefore, is dependent upon the thickness of the characters or matrices composing the line and not merely upon the number of characters included in the line. Hence, it is necessary, during the preparation of a perforated strip representing lines of composed matter for the production of the slugs or lines of type, to totalize the several thicknesses of matrices corresponding to the code perforations made in the strip so that the operator will be apprised of the length of the line remaining as each key is operated and can thus judge the justifiability of the line.

Cooperating with the character matrices and equally determinative of the justifiability of the line are the justifying matrices, commonly known as expandible spacebands or word spacers, which comprise a portion, known as the sleeve, analogous to and having the contour of a character matrix and which is positioned in the line of matrices usually after a series of character matrices comprising a word. The sleeve has slidably

connected thereto and depending therefrom a wedge-shaped member, by means of which the spacers or spacebands are adjusted between certain ranges of thickness before the casting operation is performed. Incidentally, the thickness of the sleeve portion determines substantially the minimum thickness of the spaceband. It is essential, therefore, that the indicator denote not only the totalization of the character matrices, but also the expansibility of the spacebands, and that these two functions be performed simultaneously and the resultant effect be apparent to the operator at all times.

It has been found in practice that, to obtain the best results with the various fonts of type, spacebands of different minimum and maximum thicknesses be employed, and to compensate for this difference in spaceband sizes the device according to the present invention has been designed to adjust the differential and proportional operation of a pair of spaceband pointers to accommodate any difference in minimum and maximum thicknesses of spacebands. This adjustability is achieved by the present device through the provision of a pair of rack bars operative with the gear sectors of the spaceband pointers and capable of having the pivotal point of their operating levers varied in accordance with the particular font of type or the particular type of spaceband used in the line-casting machine for which the control tape is being prepared.

The keyboard device to which the present invention is adapted and which is fully disclosed in U. S. Patent No. 2,059,250 granted to H. L. Krum is designed to prepare a perforated tape in which the perforations represent lines of composed matter, and to take account of the aggregate lineal dimension of characters or matrices composed so that in a line of predetermined length the amount or length of the line remaining to be filled or completed will always be ascertainable. The keyboard includes keylevers arranged in a manner characteristic of typewriters and has positioned operatively with respect thereto two groups of selector elements, one of which controls a perforator and the other controls a counting mechanism; the latter totalizes the thicknesses of the characters or matrices making up the line and includes the feature of indicating to the operator the approach of the totalization to a predetermined length of line. Operative in accordance with the operation of the space key and representative of the minimum and maximum expansibility of the

spacebands inserted between words are two pointers moved differentially to indicate the condition of cumulative expansibility, so that the distance between the pointers or their spread represents the expansibility of the composed line of matrices with their associated spacebands. When the matrix pointer which indicates the cumulative thickness of the sleeves and fixed matrices, is moved into the range of the scale between the two differentially movable pointers, the operator then knows that the line of matrices represented by the perforations in the tape can be properly delivered to the line-casting machine for the casting operation.

15 A better understanding of the invention may be had from the following description, taken in conjunction with the accompanying drawings, wherein:

Fig. 1 is a fragmentary perspective view of a 20 keyboard apparatus employing the device of the present invention.

Fig. 2 is a vertical cross-sectional view of the indicating mechanism.

Fig. 3 is a front elevational view of the device 25 of the present invention.

Fig. 4 is a rear elevational view of the device of the present invention with parts broken away for purposes of illustration.

Fig. 5 is a sectional view taken on line 5—5 of 30 Fig. 4.

Fig. 6 is a view similar to Fig. 4 showing the present device in one of its operative positions.

Fig. 7 is a sectional plan view taken on line 35 1—1 of Fig. 4.

Figs. 8 and 9 are diagrammatical representations of the maximum and minimum spaceband adjustments.

Figs. 10 and 11 are graphical representations 40 of the equations of maximum and minimum deflection.

Figs. 12, 13, and 14 are elevational views of modifications according to the present invention.

Referring now to the drawings wherein like reference characters indicate the same part throughout the several views, the present invention is shown in the specific embodiment herein described in connection with the indicating device disclosed in the aforementioned patent. The indicating mechanism comprises a sectoral or fan-shaped dial 20 (Figs 1 and 3) similar to that shown in the aforementioned patent except that it is provided with a movable scale member 21 operable with the minimum spaceband pointer 22 as disclosed in the U. S. Patent No. 2,021,151 granted to W. W. Morey. Movable with respect to the scale are an index hand or matrix pointer 23 and a pair of spaceband pointers 22 and 24. In the present embodiment, space band pointer 22 is connected to and propels the scale. The matrix pointer 23 is rendered variably movable along the arcuate edge of the scale 21 by means of the counting mechanism disclosed in the aforementioned U. S. Patent No. 2,059,250 which is variably operated in accordance with the widths of the characters composed in the line. Briefly, the operation of the counting mechanism is controlled by a series of keys 25, Fig. 1, through the instrumentality of selector mechanisms contained within the base of the keyboard device.

70 Referring to Fig. 2, the matrix pointer 23 is shown as disposed between a flanged member 26 and an annular member 27, and, as described in U. S. Patent No. 2,059,250, the matrix pointer 23 is rendered movable with the flange member 75 26 by reason of the pressure imparted thereon

by a spring 28 through the instrumentality of a rod 29 and member 27 integral therewith. Gear 31 secured to the flange member 26 is in mesh with a pinion 32, the rotation of which is variably controlled by the counting mechanism (not shown, but fully described in U. S. Patent No. 2,059,250) through the medium of shaft 33 and gear wheel 30 (Fig. 1), the rotation thereof in varying amounts being transmitted through gear 31 to the matrix pointer 23.

As shown in Fig. 2, the dial 20 is pivotally mounted at 34 to bracket 35 and is adjustably set through slot and screw adjustment 36 (Fig. 3). As indicated in Figs. 1 and 3, dial 20 has

slidably mounted along its outer edge, by means of slots 37 and 38 coating with stud screws 39 and 40, respectively, the scale 21. The length of slots 37 and 38 is determined by the number of spacebands normally required in a line of composed matter and it may be assumed for all practical purposes to be of such length as to permit a movement of the spaceband pointers a distance representative of ten spacebands. Scale 21 is provided along its arcuate edge with a series of graduations which in the present embodiment of the invention represent keyboard "ems", so called because the space between two graduations (disregarding the short marks which in the present instance merely represent one-half "ems" to enhance the readability of the scale) is proportionate to the thicknesses of the "em" quads of the various fonts of type. Since the scale is

utilizable for any font of type these keyboard "ems" represent proportions and not actual dimensions of type faces, the only requisite being that the characters in the various fonts of type have the same unit groupings as set forth in U. S. Patent No. 2,059,250. The length of line to be composed is predetermined and is represented by the distance between matrix pointer 30 41, Figs. 1 and 4, and the zero position on the scale. Thus, the adjustable stop 41 and the zero position on the scale cooperate to define the range of movement of the matrix pointer 23. The reverted end 45 of the matrix pointer 23 moves along the edge of the scale from left to right (Fig. 1) towards zero in response to the totalization or accumulation of the matrix or character thicknesses by the counting mechanism. Thus, the distance 50 from the pointer 23 to zero at any instance indicates the amount of space left in the line to be filled when the line contains no spacebands. Normally, however, when spacebands are inserted in the line the space remaining to be filled varies with the number of spacebands inserted or introduced in the line. So, to indicate the 55 justifiability of the composed line, the pair of pointers 22 and 24 are provided, the distance between the pointers indicating the cumulative amount of expansibility of the spacebands. The 60 movements of the spaceband pointers 22 and 24 must likewise be translated into keyboard "ems"; that is, the thickness of the large end of the spaceband, for example, must be expressed in "ems" instead of in inches so that the movement of the maximum spaceband pointer 24 along the arcuate edge of the scale will also read in terms of keyboard "ems". In other words, the deflection 65 of the spaceband pointers for each different spaceband in order to be commensurate with the deflection of the matrix pointer 23 must be expressed in keyboard "ems".

To determine the deflection of the spaceband pointers in terms of "ems", the thickness of the 70 75 80 85 90 95 100 105 110 115 120 125 130 135 140 145 150 155 160 165 170 175 180 185 190 195 200 205 spaceband (either maximum or minimum) in inches is divided by the set size of the font, in inches. The set size of the font, as is known in the art, is derived from the set size of the "em" quad in the particular font. The term, set size, is employed to specify the width of the type body measured "linewise" and is measured in points—the printer's unit of measure. The set size of a font is expressed in terms of the set size of the "em" quad of that font, thus, if the "em" quad of a font is four points in width, then the set size of that particular font is said to be "4-set". To obtain the set size of the "em" quad (or in the last analysis, any type face) in inches, it is only necessary to multiply the set size, which is generally given in "points", by the linear equivalent of a "point", which is .01383 inch (approximately 1/72 of an inch). Expressed in terms of formulae, in which:

20 S_x = maximum thickness of spaceband
and,

S_m = minimum thickness of spaceband,
(1) Deflection per spaceband (in "cms") =

25
$$\frac{S_x \text{ (in inches)}}{\text{set size in inches}} \text{ (maximum)}$$

and,

(2) Deflection per spaceband =

30
$$\frac{S_m}{\text{set size}} \text{ (minimum)}$$

Formula (1) is employed in determining the deflection of the maximum spaceband pointer 24 in keyboard "ems", and Formula (2) is employed 35 in determining the deflection of the minimum spaceband pointer 22 in keyboard "ems". The applicability of the forgoing formulae to the present invention will be shown hereinafter and will be more clearly understood following a detailed description of the preferred structure 40 adapted to practice the invention.

The scale 21 being movable with the minimum spaceband pointer 22, the matrix pointer 23 indicates not only the cumulative thicknesses of 45 the character matrices in the composed line, but also there is added thereto the thicknesses of the sleeves of the one or more spacebands in the line, as is clearly set forth in U. S. Patent No. 2,021,151.

50 The differential or proportionate movements of pointers 22 and 24 toward the left (Fig. 1) is accomplished by the mechanism according to the present invention indicated generally by the numeral 42, Fig. 1, which is actuated by a periodically reciprocated bar 43. Similarly, as disclosed in U. S. Patent No. 2,059,250, the bar 43 is slidably mounted in a bracket 44 supported on the base 45, Figs. 4 and 6, and on stud 46 also secured to the frame and has one end secured, 55 as shown in Fig. 1, to one arm of a bell crank lever 47. The bell crank lever 47 is pivoted on a fixed pivot 48 and has its other arm operatively related to a cam 49 mounted for cyclic rotation through suitable clutch mechanism responsive to 60 the actuation of each of the keylevers on a continuously rotating shaft 51 which is in turn rotated by power communicated from a continuously rotating motor 52, all as fully described in U. S. Patent No. 2,059,250. Cam 49 is provided 65 with two similar cam surfaces to permit two cycles of operation for each complete revolution of the cam; that is, cam 49 is permitted to rotate only 180° or one-half revolution during each cycle of operation. Bell crank 47 is maintained in 70 operative relation with cam 49 by a spring 53.

Pivotedly carried on bar 43, as shown in Fig. 4, is a stepping pawl 54 which is normally spring-urged in a clockwise direction, Fig. 4, and is adapted upon actuation of bar 43 to cooperate with a ratchet rack 55 associated with the adjustable spaceband indicating unit 42. For each reciprocation of bar 43, the pawl 54 will also be reciprocated but the effectiveness thereof is dependent upon other elements. In the exemplification of the invention herein illustrated the effectiveness of stepping pawl 54 on the ratchet rack 55 is determined or established upon the operation of a space key 50 (Fig. 1) which through a rocking rod and attached radial arm articulated by pin and slot to a lever 56 pivoted at its rear end controls the position of a vertically extending element 57, Figs. 1 and 4. The element 57, as shown in Fig. 4, is mounted loosely on a bushing or screw secured to lever 56. With this construction the element 57 is free to move to the right or left on the bushing or screw. The element 57, as clearly shown in Fig. 1, has its upper portion formed as a hook which engages the horizontal arm of a lever 58, Fig. 4, also pivotally carried on bar 43, and is held against a stop 59 by a spring 60, one end of which is secured to the element 57 and the other end to a post on the bar 43. Upon the depression of the space key 50, lever 56 is operated and causes the downward movement of element 57 and rotates lever 58 to a limited extent. The sloping arm of pivoted lever 58 is notched near its extremity and engaging the shoulder thereof is one arm of a lever 61 which is also pivotally carried on the bar 43 and consequently moves with it. Both levers 58 and 61 are under the influence of springs arranged to move these elements toward each other, as clearly shown in Figs. 4 and 6. Upon the downward movement of element 57, the lever 61 will be released from the shoulder formed on 40 the lever 58 and the pawl 54 will be moved about its pivot 62 by the action of lever 61 through its associated spring. Now, when cam 49 rotates, operating its bell crank follower 47 clockwise, and the bar 43 is moved to the right, 45 as shown in Fig. 4, (or to the left, as shown in Fig. 1) and with the pawl 54 engaging one of the teeth in the ratchet rack 55, the rack 55 will be moved in the same direction, thus causing the movement of the pointers 22 and 24 through their associated gears 63 and 64, respectively. During the rightward movement of bar 43 and immediately following the stepping of the ratchet rack 55, the depending portion of lever 61 coacts with a fixed stop member 90 to effect 50 the reengagement of lever 61 with the shoulder on lever 58 preparatory to a subsequent actuation of keylever 56.

The ratchet rack 55 is adjustably secured through slots and clamping screws 65 and 66 to a 60 substantially U-shaped member 67 slidably mounted on studs 68 and 69 secured to the frame of unit 42. As indicated in Fig. 3, the spaceband pointers 22 and 24 are pivotally carried on a stud shaft 70 which is preferably arranged in coaxial alignment with rod 29, Fig. 2. As indicated in Fig. 5, the pointers 22 and 24 are U-shaped at their pivotal points to provide a substantial bearing on the pivot shaft 70. The pointers 22 and 24 are normally spring urged to their initial or zero position by individual springs 71 and 72.

As viewed in Fig. 3, there are obliquely positioned on the main frame of the unit 42 adjusting screws 73 and 74 provided at their upper extremities with thumb portions through which 75

the rotation of the respective screws is effected. Carried on the screws 73 and 74 are individual traveling blocks 75 and 76, respectively, and integral with and extending rearwardly from blocks 75 and 76 are pivot studs 77 and 78. Through the rotation of screws 73 and 74 the blocks 75 and 76 are caused to travel therealong, thus varying the position of the pivot studs 77 and 78. Having reference to Fig. 4, there are operatively related to pivot studs 77 and 78 operating levers 79 and 80, respectively, which in their normal or zero positions are disposed in parallel alignment with the adjusting screws 73 and 74. The angular positions of screws 73 and 74 are so chosen or established that the extreme angular movement or deflection of levers 79 and 80 from either side of vertical will be the same. The operating lever 79 is pivoted to a gear rack 81 which is slidably carried on a pair of studs 82 and 20 83 secured to the frame of the indicator adjusting unit 42. The lower end of operating lever 79 is provided with an open ended slot adapted to cooperate with a pin 84 secured to member 67. Gear rack 81, Fig. 4, is provided between the studs 25 82 and 83 with a dropped portion, the upper edge of which is provided with gear teeth to mesh with gear sector 83. In a similar manner, operating lever 80 is normally disposed in parallel alignment with the adjusting screw 74 and is pivotally connected to a gear rack 85 slidably mounted on the aforementioned studs 82 and 83. The lower end of operating lever 80 likewise is provided with an open ended slot to coat with a pin 86 secured to the member 67. It is to be noted that 30 gear racks 81 and 85 are movable on studs 82 and 83 independently of each other. The upper edge of gear rack 85 is provided with gear teeth adapted to mesh with gear sector 84.

There is also associated with the ratchet rack 55 a holding pawl 87 normally urged into engagement with the ratchet rack 55 by a spring 88. The pawl 87 is pivotally carried by a bracket 89 attached to the frame of unit 42. Thus, when pawl 87 is reciprocated, as previously described, the member 67 is moved for each effectiveness of said pawl to the right an amount corresponding to the right-hand movement of bar 43 and held thereat by the holding pawl 87.

As previously set forth, the number of spacebands normally insertable in a line of composed matter has been established, for all practical purposes, at ten spacebands. Therefore, to apprise the operator of the fact that ten spacebands have been inserted in the line of composed matter which he is preparing, a signal bell 91 is provided which is carried on the frame of the unit 42 as indicated at the right-hand of Fig. 4 (or the left-hand of Fig. 3). A hammer 92 is pivotally carried at 93, Fig. 4, and is provided with a cam portion 94 to coat with a yieldable cam member 95 pivoted at 96 on the member 67 such that, when the member 67 is operated in a step-by-step manner to the extent of ten teeth on the ratchet rack 55 representative of ten spacebands, the cam member 95 will coat with cam portion 94 to effect a counterclockwise rotation of hammer 92 against the action of its spring 97, and when the cam member 95 passes the member 94 upon the actuation of the member 67 corresponding to the tenth spaceband, the hammer 92 will be free to respond to the action of its spring 97 to strike bell 91, thereby signalling the operator that ten spacebands have been inserted in the line.

To effect the restoration of the indicating

mechanism to its initial position; that is, to effect the return of the pointers 22, 23, and 24 to their zero or beginning-of-line position, the elevator or end-of-line key of the series of keys 25 is actuated, the actuation of which effects mechanically, as set forth in U. S. Patent No. 2,059,250, through lever 88 and link 89, Fig. 2, the rotation of bell crank 101 in a counterclockwise direction about pivot 102 to cause rod 28 to move to the left against the action of spring 28 to disable the clamping effect of disc 27 upon the matrix pointer 23 and to permit pointer 23 to be returned to its initial position against the adjustable abutment 41 by a spring actuated lever 103 acting on a cord 104 attached to pointer 23, as fully described in U. S. Patent No. 2,059,250.

Simultaneously with the actuation of bell crank 101, lever 88 also acts through link 105 (Fig. 2) to rotate lever 106 about its pivot 107 to cause the counterclockwise rotation of holding pawl 87, Fig. 4, thus permitting the member 87 to be returned to its left-hand or normal position, as viewed in Fig. 4, by a spring 108, more clearly shown in Fig. 3. Fig. 6 illustrates the device according to the present invention in its fully operated position, wherein the ratchet rack 55 is shown as having been actuated to its extreme right-hand position by pawl 84, which movement has been transferred through gear racks 81 and 85 and their respective gear sectors 83 and 84 to spaceband pointers 22 and 24, respectively. It is also observed that the scale portion 21 has been moved by and with the minimum spaceband pointer 22.

The mechanism of the present invention is conditioned to operate for various spacebands by adjusting the pivotal points 77 and 78 to correspond with predetermined calculations, derived from the previously mentioned formulae, which may be incorporated for practical use into either a table or suitable graphs. In the present disclosure, Figs. 10 and 11 illustrate graphs or curves which have been plotted in accordance with these calculations.

Figs. 8 and 9 represent diagrammatically the movements of the operating levers corresponding to the adjustments established. Assuming, in Fig. 8, that the pivotal point of lever 80 is established at 78, the member 85, when lever 80 has been rotated about 78 in response to the successive step-by-step movements of member 67 through the instrumentality of pawl 84 and ratchet rack 55, will be moved to the dotted line position 80'. The linear movement 161—161' will be translated through gear 84 to angular movement 163. In this manner maximum spaceband pointer 24 is moved incrementally in response to the step-by-step movement of the ratchet 55 from the full line position in Fig. 8 to the dotted line position 80'. Assuming that the pivotal point has been adjusted to 78', the distance of travel of point 161 and likewise gear rack 85, the point 86 moving the distance 86—86' the same as before, will be less and consequently the angle of rotation of pointer 24 will be correspondingly less. In the same manner if the pivotal point 78 is lowered, a correspondingly greater movement of point 161 will be attained and a correspondingly greater movement of pointer 24 will result.

Referring to Fig. 9, the same analogy is apparent. The variation of the pivotal point 77 with the movement 84—84' remaining constant will effect a different linear movement of point 164 along line 164—164', which variable movement 75

will be imparted to gear rack 81 and translated through gear sector 83 to pointer 22.

The graphs illustrated in Figs. 10 and 11 plotted in accordance with Formulae (1) and (2), respectively, afford a convenient method of communicating to the operator of the keyboard apparatus the information or data requisite to effect the necessary adjustments of pivots 11 and 18 to render the device of the present invention effective for any particular spaceband. That is, the operator, knowing the font of type for which the tape is to be prepared, predetermines the size of spaceband which will produce the best copy and adjusts the pivots 11 and 18 (Fig. 3) accordingly. Assuming, for example, that the spaceband represented by curve 1 (which will hereinafter be called the No. 1 spaceband) is selected for use with an 8-set font of type, the operator observes from the chart shown in Fig. 10 that the deflection of the maximum pointer for ten spacebands is four and one-half keyboard "ems". Incidentally, the reason for reading this deflection in terms of ten spacebands is because the reading for one spaceband would probably be too small to readily effect an accurate adjustment. Noting this reading, the operator thereupon adjusts the traveling block 16 carrying the pivot 18 so as to read on the scale adjoining the block four and one-half keyboard "ems". Further, if the adjustment is to be for the No. 1 spaceband with a 4-set font of type, the reading from the table in Fig. 10 would be nine keyboard "ems" and the traveling block 16 would be set at the point shown in Fig. 3. Once the curves 35 have been plotted in accordance with the foregoing formulae, it is a simple matter to take the readings therefrom and to adjust the pivots 11 and 18 accordingly. The adjustment for the minimum spaceband pointer is made in accordance with the curves plotted in Fig. 11. For example, assuming that the No. 1 spaceband is to be used with a 4-set font of type, the reading would be five and one-half keyboard "ems" and the traveling block 15, Fig. 3, would therefore be adjusted so that the index pointer thereon would coincide with the graduation on the adjoining scale representative of five and one-half keyboard "ems".

An alternate method of adjustment which contemplates the use of the movable type of scale 21, but without the use of the scales adjoining the traveling blocks 15 and 16, is as follows: The indicating mechanism is first restored to its normal position and the matrix pointer 23 is set to any convenient unit graduation on scale 21. It is apparent from the foregoing disclosure that the matrix pointer 23 may be moved manually against the action of spring pressed disc member 27 (Fig. 2) by merely exerting upon pointer 23 sufficient force to overcome the frictional pressure thereagainst. The space key is thereafter operated ten consecutive times, moving as is already understood, the scale 21, a distance equal to the movement of the minimum spaceband pointer 22. Also, the selected graduation at which the matrix pointer was set is likewise moved in the same direction an equivalent distance. Now, using this selected graduation as the zero point and taking from Fig. 11 the reading corresponding to the spaceband and font of type to be used, the minimum spaceband adjusting screw 13 is rotated until the matrix pointer 23 coincides with the aforementioned reading. For example, assuming that the matrix pointer is set at graduation 35 when the scale 21 is in its normal position,

and that the space key is operated ten consecutive times, the matrix pointer 23 remains stationary, but the scale 21 and likewise graduation 35 thereon move to the left, as viewed in Figs. 1 and 3, a cumulative distance representative of the said ten consecutive operations. Now, assuming that the reading taken from Fig. 11 for the No. 1 spaceband and for a 4-set font of type is four and one-half keyboard "ems" and taking the graduation of 35 as the zero position, the minimum adjusting screw is rotated until the graduation 35 is four and one-half keyboard "ems" to the left of the stationary matrix pointer 23, or until the matrix pointer 23 reads 30½; the effect of turning the screw 13 being to alter the deflection of minimum spaceband pointer 22 and likewise the scale 21. This completes the adjustment for minimum spaceband pointer 22. Now, to ascertain the adjustment of the maximum spaceband pointer the difference between the readings obtained from Figs. 10 and 11 is used, it being recalled that the space between the pointers 22 and 24 represents the usable expansibility of a spaceband. Thus, for example, the reading for the No. 1 spaceband for a 4-set font of type is taken from Figs. 10 and 11 by subtracting the reading, viz. 5½ "ems", of Fig. 11 from the reading, viz. 9 "ems", of Fig. 10, which difference is 3½ "ems". Now without disturbing the conditions set up by the operation of the space key ten consecutive times, the adjustment is made by turning the maximum adjusting screw 14 until the maximum spaceband pointer 24 is 3½ keyboard "ems" from the zero position on the scale 21. The pivots 11 and 18 have now been properly adjusted for a No. 1 spaceband and a 4-set font of type, and the key for restoring the pointers and scale to their original position can now be operated, and subsequent operations of the space key will cause a deflection of spaceband pointers 22 and 24 a distance representative of the minimum and maximum thicknesses of the No. 1 spaceband indicated in the graphs in Figs. 10 and 11.

The same procedure of adjustment is followed for spacebands represented by the curves 2 and 3 in Figs. 10 and 11. In actual practice, these curves would be plotted to a larger scale to facilitate the procurement of readings for the various spacebands; also, other curves would be added to represent other commercial sizes of spacebands.

General operation

The details of the apparatus having been described, a further understanding of the structure constituting the present invention can be obtained from the following detailed description of its operation.

Referring to Fig. 1, the tops 25 of the keylevers 60 carry indicia (not shown) analogous to the well-known typewriter keyboards wherein two sets of designations are used, one for the lower case and the other for the upper case, a shift key and an unshift key being provided to condition the general apparatus to function for counting and perforating in accordance with whether the tape is to be perforated and the indicating and counting mechanism operated for upper or lower case characters. The perforating, counting, and indicating operations proceed in the manner disclosed in U. S. Patents Nos. 2,021,151 and 2,059,250, the only difference being that in the present instance means have been provided to accommodate various sizes of spacebands, which 75

adjustment facility did not obtain in the structures of the foregoing patents.

Before commencing to operate the apparatus, the operator at first sets the spaceband adjustments 15 and 16 to correspond to a predetermined spaceband in the manner previously described.

Assuming that the apparatus is in its normal beginning-of-line position with its matrix pointer 23 against adjustable stop 41 and the spaceband pointers 22 and 24 and scale 21 in the initial or zero position as shown in Fig. 3, a single operation of the space key 50 will cause, through link 57, the lever 58 to be tripped from engagement with lever 61 which will be rotated a slight amount in a counterclockwise direction by its spring to bring stepping pawl 54 into engagement with ratchet rack 55 (Figs. 4 and 6). Simultaneously with the tripping of lever 61 the keylever 56, as clearly set forth in U. S. Patent No. 2,059,250, operates a universal bar which trips a cyclically operated clutch to initiate the rotation of the cam 49 (Fig. 1) to effect the reciprocation through lever 47 of bar 43. A single reciprocation of bar 43 will cause the member 67 to be actuated one step toward the right and to be retained therat by the holding pawl 81. Operating bars 79 and 80 will be rotated about their pivots 77 and 78 a slight amount commensurate with a single step movement of ratchet rack 55. The movements of operating bars 79 and 80 will be transferred to gear racks 81 and 85, respectively, and in turn to gear sectors 63 and 64, respectively, to cause a deflection in pointers 22 and 24 an amount representative of the minimum and maximum thicknesses of the predetermined spaceband. Succeeding operations of the space key 50 will cause the member 67 to be stepped in the same manner for each effectiveness thereof, which movement will result in a further deflection of pointers 22 and 24. When the space key has been operated, say, for example, ten times, the member 95 on member 67 will cooperate with the cam surface 94 to effect the ringing of the bell 91, thereby signalling the operator that ten spacebands have been accounted for in the line of composition for which the tape is being prepared. The operator then depresses the elevator key, the effect of which is to restore the indicating mechanism to its normal beginning-of-line position. The effect of depressing the elevator key is to actuate lever 98, Fig. 2, to in turn operate levers 106 and 101 to simultaneously effect the return of the matrix pointer 23 to its position against stop 41 and to rotate holding pawl 81 slightly in a counterclockwise direction, Fig. 4, to permit member 67 to be returned to its extreme rightward position, as viewed in Fig. 3, by spring 108.

Although the foregoing disclosure is predicated upon the fact that the graduations on scale 21 denote keyboard "ems", it is immaterial to the adaptability of the device of the present invention whether the graduations denote "ems" or "picas." A "pica", as is known in the printing art, is a unit of measurement which is used to designate the widths of columns and lengths of lines, and is equivalent to 12 "points"; that is, 12 "points" make a "pica" and 6 "picas" are assumed to make an inch. However, this is not absolutely correct, for, to avoid a repeating decimal, the "pica" is fixed as .166 inch; whereas if there were exactly 6 "picas" to the inch, the figure or digit 6 would repeat to infinity. Thus, it is apparent from the foregoing that the "em" is a relative unit of measurement, depending for its actual di-

mensions upon the particular font used, while a "pica" is an absolute unit of measurement.

Therefore, a scale denoting "picas", is effective to totalize matrix widths without first determining the set size of the font of type, because the term "em", as is obvious from the previous disclosure, is used merely to indicate a proportion, while a "pica" is an absolute linear measurement or dimension, and hence in the foregoing formulae the set size becomes unity or 1, so that the deflection per spaceband is equal to S_x , or S_n in formula (1) or (2), respectively. In the event, then, that a "pica" scale is employed the counting mechanism of the keyboard perforator and counter is designed to embody a greater number of counting bars or elements depending upon to what fraction of a "point" it is desired to count. Obviously, the scope of the invention is not dependent upon the number of units into which an "em" or a "pica" is divided. Consequently, with the use of a "pica" scale the graduations adjoining the traveling blocks 16 and 17 need only be changed to establish markings to represent the various spacebands; for example, the graduations thereon may be predetermined and suitably marked for the commercial sizes of spacebands, either by number or otherwise, and instead of the graphs shown in Figs. 10 and 11 the operator is provided with a table apprising him of the minimum and maximum sizes of the various spacebands according to an identifying number assigned thereto.

Modifications

Modifications of the present invention are illustrated in Figs. 12, 13, and 14. In the modified form shown in Fig. 12, the pawl 54 is carried as before on reciprocating bar 43 and is actuated into cooperative engagement with ratchet rack 115 (analogous to rack 55 of the previously described structure) by the lever 61 similarly as previously set forth. Rack 115 is slidably mounted on studs 116 and 117 secured to the frame 118 of the adjustable spaceband indicating unit. Rack 115 is pivotally articulated to an operating lever 119 through a pivot stud 120, analogous to lever 79 in the preferred embodiment of the present invention, which lever is pivoted to a gear rack 121 and coacts with adjustable pivot 122 in a manner similar to that described in connection with the preferred form of the invention. Gear rack 121 cooperates with gear sector 123 of the maximum spaceband pointer 124. Also pivoted to the gear rack 121 is the operating lever 125 which is provided with a slot adapted to coact with a pivot stud attached to a gear rack 126, located below gear rack 121, which cooperates with gear sector 127 of minimum spaceband pointer 128. Gear racks 121 and 126 are slidably mounted on shoulder screws attached to frame 118 as clearly shown in Fig. 12. Operating lever 125 also cooperates with an adjustable pivot 129 adjustably associated with the frame 118 in a manner similar to that disclosed in the preferred form of the invention.

The operation of this form of the invention is as follows: When the pawl 54 is reciprocated, as already described, it functions to actuate ratchet rack 115 in a step-by-step manner for each reciprocation thereof, the rack 115 being held in each instance by the holding pawl 81. This movement is imparted through pivot stud 120 to operating lever 119 which pivots about the adjustable pivot 122 to actuate gear rack 121 to the left, which movement is imparted through

gear sector 123 to maximum pointer 124. As gear rack 121 is actuated toward the left, operating lever 125 is caused to rotate about the adjustable pivot 128 and simultaneously to carry gear rack 126 toward the left due to its pivotal connection 131 thereto which movement is imparted to gear rack 127 and in turn to minimum spaceband pointer 128.

Through the instrumentality of adjustable pivots 122 and 129 the movements of the spaceband pointers 124 and 128 can be varied to correspond with the particular spacebands used, the adjustment thereof being determined in the same manner as described in connection with the preferred form of the invention; that is, for example, the adjustment 122 can be altered to correspond with the item or figure given in a table or set of graphs which may be prepared for the operator. Likewise, the adjustment 129 may be altered to change the movement of the minimum spaceband pointer 128 to correspond with the figures given in said table or graph. The adjustment 122 is identical to that described in the preferred form and is indicated in keyboard "ems". The adjustment of pivot 129, however, is not indicated by keyboard "ems", but is determined by the ratio of the two spaceband pointer movements.

In the modification shown in Fig. 13, a different cam and pinion assembly 135 is provided for each spaceband. In this form of the invention a ratchet rack 136 is slidably mounted on studs secured to frame 137 of the indicator unit and is operated in a step-by-step manner, similar to 35 that previously described, by the reciprocating pawl 54. Pivotaly articulated to the ratchet rack 136 is an operating lever 138 which is pivoted to a gear rack 139 slidably carried on studs secured to the frame 137. Operating lever 138 cooperates with an adjustable pivot 141, in a manner similar to that previously described, which pivot is adjustable in accordance with the set size of the font of type in connection with which the spaceband is to be used. Cooperating 40 with the gear sector 139 is the pinion 142 of the assembly 135. The assembly 135 is provided with two different cams; namely, cam 143 for the minimum spaceband pointer 144, and cam 145 for maximum spaceband pointer 146.

The operation of the form of the invention shown in Fig. 13 is apparent. The proportions of the cams 143 and 145 being predetermined to suit the particular spacebands, the adjustment 141 is made to correspond with the set size of the 50 font with which the particular spaceband is used. For different spacebands these cams would be changed.

The modification shown in Fig. 14 is quite similar to that shown in Fig. 13. Instead of having 60 circular cams associated with a pinion and rack an accurately milled cam member 151 is provided which is slidably carried on studs secured to the frame 152 of the adjustable spaceband indicator unit. Cooperating with the cam surfaces of member 151 are follower rollers 153 and 154 of minimum spaceband pointer 155 and maximum spaceband pointer 156, respectively. The cam surfaces of member 151 are determined by the same formulae as set forth in the preferred form 65 of the invention and are hyperbolic in contour. The cam member 151 is actuated through operating lever 157 by a ratchet rack 158 slidably carried on pivot studs attached to frame 152. Rack 158 is operated by the reciprocating pawl 54 in a 70 manner previously described. The operating

lever 157 is pivoted to rack 158 and when rack 158 is actuated, the operating lever 157 is caused to rotate about the adjustable pivot 159 and to operate cam 151 toward the left (as viewed in Fig. 14) to in turn actuate spaceband pointers 155 and 156 correspondingly.

It is apparent from the foregoing description that a device has been provided which renders the keyboard perforating and counting apparatus adaptable to typesetting systems employing an indefinite number of sizes of spacebands. Although the present invention has been disclosed in connection with a perforator and counter, it is, of course, understood that the invention is capable of embodiment in many and varied applications other than that specifically disclosed without departure from the spirit and scope of the invention as defined in the appended claims.

What is claimed is:

1. In a keyboard apparatus, a pointer member movable under certain operating conditions, a series of keys corresponding to a series of characters, means operated upon the depression of each of said keys for effecting the movement of said pointer member an amount predetermined by the particular key depressed, a special key, a pair of pointer members, means actuated by said special key for controlling the movement of said pair of pointer members differently according to the number of times said special key is depressed, and means associated with said pair of pointer members to vary the degree of movement for each operation of the special key.

2. In combination with a keyboard perforator suitable for the production of perforated tape representing justifiable lines of matrices, a scale, an index member movable variably with respect to said scale to show the totalized width of matrices in the line at any time, a pair of pointers movable variably to show the amount of justification possible in the line at any time, and means to vary the independent movements of said pointers to correspond to the justifying matrix to be used.

3. In combination with a keyboard perforator suitable for the production of perforated tape representing lines of composition, a member movable under certain operating conditions, a pair of other members operable under other operating conditions and cooperative with said member to determine the justifiability of a line, and means to vary the operating conditions of said pair of members.

4. In an apparatus for producing perforated strips for the control of typographical machines, a keyboard including character keys and a spacer key controlling the perforation of the strip, a counting mechanism controlled by said keyboard for indicating respective widths of characters individual to said keys and justifiability of a line, including a scale, a pointer, power driven mechanism for moving said pointer relatively to said scale in varying amounts, a pair of pointers, and gearing driven from a common source of power for rotating said pair of pointers different distances for each effectiveness thereof, and means to vary the cooperative relation of said gearing to effect a corresponding change in the movement of said pointers.

5. In combination with a keyboard perforator suitable for the production of perforated tape representing lines of composition, a scale, a pointer movable variably with respect to said scale to indicate the cumulative widths of char-

acters, a pair of pointers, and gearing operable from a common source of power for rotating said pair of pointers different distances for each effectiveness thereof for indicating a different condition, and means for varying the operation of said gearing.

6. In a keyboard apparatus, a pointer member movable under certain operating conditions, a plurality of keys corresponding to a series of characters, means operated upon the depression of each of said keys for effecting the movement of said pointer member an amount predetermined by the particular key depressed, a special key, a pair of pointer members, means actuated by said special key for controlling the movement of said pair of pointer members differentially relatively to the member pointer controlled by the character keys, and means for varying the differential operation of said pair of pointer members.

7. In combination with a keyboard perforator suitable for the production of perforated tape representative of consecutive characters and word spacers, a series of keys, a scale, a pointer movable variably with respect to said scale in response to the operation of said keys to indicate the cumulative widths of characters, a pair of pointers, adjustable means for operating said pointers differentially to indicate the cumulative expansibility of the word spacers, and a special key operable through the instrumentality of said means to effect a relative change in said pair of pointers to correspond to the increment of expansibility provided by a spacer.

8. In an apparatus for preparing tapes for the automatic control of linecasting machines, means for indicating amounts representative of matrix widths, means to indicate the justifiability of the line of composed matter, means for effecting the relative movement between said means to change the normal zero position of justifiability, and means to vary the operation of said second recited means to correspond to predetermined extents of justifiability.

9. In combination, a scale, a member movable with respect to said scale under certain operating conditions, a pair of members operable under other operating conditions, means controlled by one of said pair of members to effect a change in the zero position of said scale in response to each operation of said pair, and means to vary the extent of said change.

10. In combination with a keyboard perforator suitable for the production of perforated tape representative of consecutive characters and word spacers, a series of keys, a scale, a pointer movable variably with respect to said scale in response to the operation of said keys to indicate the cumulative widths of characters, a pair of pointers, means comprising a gear sector and a gear rack individual to each of said pointers to operate said pointers differentially, adjustably pivoted operating levers therefor, pawl and ratchet means for actuating said operating levers, a special key, and means operably controlled by said special key to actuate said pawl and ratchet means to effect through the instrumentality of said gear racks and gear sectors a relative change in said pair of pointers to correspond to the increment of expansibility provided by a spacer, all of said pointers cooperating to indicate continuously a condition of justifiability.

11. In combination with a keyboard perforator suitable for the production of perforated tape representative of consecutive characters and word

spacers, a series of keys, a scale, a pointer movable variably with respect to said scale in response to the operation of said keys to indicate the cumulative widths of characters, a pair of pointers, means controlled by one of said pair of pointers to effect a change in the zero position of said scale in response to each operation of said pair whereby the increment of movement of said one of said pair of pointers is superadded to the indication of said first recited pointer, means comprising a gear sector and a gear rack individual to each of said pointers to operate said pointers differentially, adjustably pivoted operating levers therefor, pawl and ratchet means for actuating said operating levers, a special key, and means operably controlled by said special key to actuate said pawl and ratchet means to effect through the instrumentality of said gear racks and gear sectors a relative change in said pair of pointers to correspond to the increment of expansibility provided by a spacer, all of said pointers cooperating to indicate continuously a condition of justifiability.

12. In combination with a keyboard perforator suitable for the production of perforated tape representative of consecutive characters and word spacers, a series of keys, a scale, a pointer movable variably with respect to said scale in response to the operation of said keys to indicate the cumulative widths of characters, a pair of pointers, means comprising a gear sector and a gear rack individual to each of said pointers to operate said pointers differentially, adjustably pivoted operating levers therefor, a slideable carriage comprising a ratchet rack and a cam means, a special key, and a reciprocable pawl means operably controlled by said special key for actuating through said ratchet rack said operating levers and said carriage to effect through the instrumentality of said gear racks and gear sectors a relative change in said pair of pointers to correspond to the increment of expansibility provided by a spacer, all of said pointers cooperating to indicate continuously a condition of justifiability.

13. In combination, a scale, a scale indicating means movable under certain operating conditions, a mechanism for operating the indicating means, and means comprising an interchangeable cam member for adjusting the operative relationship between said indicating means and said mechanism for varying the degree of movement of the indicating means upon the operation of the mechanism.

14. In combination with a keyboard suitable for the production of perforated tape representative of consecutive characters and word spacers, a series of keys, a scale, a pointer movable variably with respect to said scale in response to the operation of said keys to indicate the cumulative widths of characters, a pair of pointers, means comprising a gear rack and pinion to operate said pointers differentially, an adjustably pivoted operating lever therefor, pawl and ratchet means for actuating said operating lever, a special key, and means operably controlled by said special key to actuate said pawl and ratchet means to effect through the instrumentality of said first recited means a relative change in said pair of pointers to correspond to the increment of expansibility provided by a spacer.

15. In combination with a keyboard suitable for the production of perforated tape representative of consecutive characters and word spacers, a series of keys, a scale, a pointer movable vari-

- ably with respect to said scale in response to the operation of said keys to indicate the cumulative widths of characters, a pair of pointers, means to operate said pointers differentially, an adjustably pivoted operating lever therefor, pawl and ratchet means for actuating said operating lever, a special key, and means operably controlled by said special key to actuate said pawl and ratchet means to effect through the instrumentality of said first recited means a relative change in said pair of pointers to correspond to the increment of expansibility provided by a spacer. 5
16. In combination, a scale, a scale indicating means movable under certain operating conditions, a mechanism for operating the indicating means, and means comprising a first adjustable means operable under other operating conditions and a second adjustable means operable proportionally through the agency of said first adjustable means for adjusting the operative relationship between said indicating means and said mechanism for varying the degree of movement of the indicating means upon the operation of the mechanism. 10
17. In combination, a scale, a scale indicating means movable under certain operating conditions, a mechanism for operating the indicating means, a pawl and ratchet means, means comprising a first adjustable means operated by said pawl and ratchet means and a second adjustable means operable proportionally through the agency of said first adjustable means for adjusting the operative relationship between said indicating means and said mechanism for varying the degree of movement of the indicating means upon the operation of the mechanism. 15
18. In combination, a scale, a pair of members operable under certain operating conditions, means controlled by one of said pair of members 40 to effect a change in the zero position of said scale in response to each operation of said pair, and means to vary the extent of said change. 20
19. In combination, a scale, a pair of members movable with respect to said scale, means comprising a gear sector and a gear rack individual to each of said members to operate said members differentially, a reciprocating mechanism for operating said means, and means to vary the extent of operability of said means. 25
20. In combination, a scale, means movable with respect to said scale under certain operating conditions, a mechanism for operating said means, and means comprising an interchangeable 30
- cam member for adjusting the operative relationship between said means and said mechanism for varying the degree of movement of said first recited means upon each operation of said mechanism. 35
21. In combination, a scale, means movable with respect to said scale under certain operating conditions, a mechanism for operating said means, and means comprising a first adjustable means operable under other operating conditions and a second adjustable means operable proportionally through the agency of said first adjustable means for adjusting the operative relationship between said first recited means and said mechanism for varying the degree of movement of said first recited means upon each operation of said mechanism. 40
22. In combination with an apparatus for producing control strips representing lines of composition, a scale, an index member movable with respect to said scale under certain operating conditions, a pair of members movable differentially with respect to each other and cooperable with said index member to indicate a condition of justifiability, a mechanism for operating said pair of members, and adjustable means for changing the operative connection between said pair of members and said mechanism to vary the degrees of movement of said pair of members upon each operation of said mechanism. 45
23. An apparatus including a series of keys, a scale, means movable with respect to said scale under certain operating conditions, a mechanism responsive to certain ones of said keys for operating said means, means responsive to one of said keys for cooperating with said first mentioned means to indicate a predetermined condition, and means for adjusting the operative relationship between said first recited means and said second recited means for thereafter varying the degree of movement of said second recited means upon each operation of said one of said keys. 50
24. In combination, a scale, a pair of members movable with respect to said scale, means comprising proportionally adjustable instrumentalities to actuate said members, and reciprocating mechanism for operating said means. 55
25. In combination, a scale, a pair of members movable with respect to said scale, means comprising a proportionally adjustable linkage arrangement to actuate said members, and reciprocating mechanism for operating said means. 60

EDWARD S. LARSON.

CERTIFICATE OF CORRECTION.

Patent No. 2,083,608.

June 15, 1937.

EDWARD S. LARSON.

It is hereby certified that error appears in the printed specification of the above numbered patent requiring correction as follows: Page 8, first column, line 17, claim 6, for "member pointer" read pointer member; and second column, line 33, claim 12, for "differently" read differentially; and that the said Letters Patent should be read with these corrections therein that the same may conform to the record of the case in the Patent Office.

Signed and sealed this 19th day of October, A. D. 1937.

(Seal)

Henry Van Arsdale.
Acting Commissioner of Patents.

- ably with respect to said scale in response to the operation of said keys to indicate the cumulative widths of characters, a pair of pointers, means to operate said pointers differentially, an adjustably pivoted operating lever therefor, pawl and ratchet means for actuating said operating lever, a special key, and means operably controlled by said special key to actuate said pawl and ratchet means to effect through the instrumentality of said first recited means a relative change in said pair of pointers to correspond to the increment of expansibility provided by a spacer. 5
16. In combination, a scale, a scale indicating means movable under certain operating conditions, a mechanism for operating the indicating means, and means comprising a first adjustable means operable under other operating conditions and a second adjustable means operable proportionally through the agency of said first adjustable means for adjusting the operative relationship between said indicating means and said mechanism for varying the degree of movement of the indicating means upon the operation of the mechanism. 10
17. In combination, a scale, a scale indicating means movable under certain operating conditions, a mechanism for operating the indicating means, a pawl and ratchet means, means comprising a first adjustable means operated by said pawl and ratchet means and a second adjustable means operable proportionally through the agency of said first adjustable means for adjusting the operative relationship between said indicating means and said mechanism for varying the degree of movement of the indicating means upon the operation of the mechanism. 15
18. In combination, a scale, a pair of members operable under certain operating conditions, means controlled by one of said pair of members 40 to effect a change in the zero position of said scale in response to each operation of said pair, and means to vary the extent of said change. 20
19. In combination, a scale, a pair of members movable with respect to said scale, means comprising a gear sector and a gear rack individual to each of said members to operate said members differentially, a reciprocating mechanism for operating said means, and means to vary the extent of operability of said means. 25
20. In combination, a scale, means movable with respect to said scale under certain operating conditions, a mechanism for operating said means, and means comprising an interchangeable 30
- cam member for adjusting the operative relationship between said means and said mechanism for varying the degree of movement of said first recited means upon each operation of said mechanism. 35
21. In combination, a scale, means movable with respect to said scale under certain operating conditions, a mechanism for operating said means, and means comprising a first adjustable means operable under other operating conditions and a second adjustable means operable proportionally through the agency of said first adjustable means for adjusting the operative relationship between said first recited means and said mechanism for varying the degree of movement of said first recited means upon each operation of said mechanism. 40
22. In combination with an apparatus for producing control strips representing lines of composition, a scale, an index member movable with respect to said scale under certain operating conditions, a pair of members movable differentially with respect to each other and cooperable with said index member to indicate a condition of justifiability, a mechanism for operating said pair of members, and adjustable means for changing the operative connection between said pair of members and said mechanism to vary the degrees of movement of said pair of members upon each operation of said mechanism. 45
23. An apparatus including a series of keys, a scale, means movable with respect to said scale under certain operating conditions, a mechanism responsive to certain ones of said keys for operating said means, means responsive to one of said keys for cooperating with said first mentioned means to indicate a predetermined condition, and means for adjusting the operative relationship between said first recited means and said second recited means for thereafter varying the degree of movement of said second recited means upon each operation of said one of said keys. 50
24. In combination, a scale, a pair of members movable with respect to said scale, means comprising proportionally adjustable instrumentalities to actuate said members, and reciprocating mechanism for operating said means. 55
25. In combination, a scale, a pair of members movable with respect to said scale, means comprising a proportionally adjustable linkage arrangement to actuate said members, and reciprocating mechanism for operating said means. 60

EDWARD S. LARSON.

CERTIFICATE OF CORRECTION.

Patent No. 2,083,608.

June 15, 1937.

EDWARD S. LARSON.

It is hereby certified that error appears in the printed specification of the above numbered patent requiring correction as follows: Page 8, first column, line 17, claim 6, for "member pointer" read pointer member; and second column, line 33, claim 12, for "differently" read differentially; and that the said Letters Patent should be read with these corrections therein that the same may conform to the record of the case in the Patent Office.

Signed and sealed this 19th day of October, A. D. 1937.

(Seal)

Henry Van Arsdale.
Acting Commissioner of Patents.
